(57) **CLAIM**

I claim the ornamental design for a hair roller, as shown and described.

DESCRIPTION

FIG. 1 is a rear perspective view of a hair roller according to this design.

FIG. 2 is a first side elevation view of the hair roller according to this design.

FIG. 3 is a second side elevation view of the hair roller according to this design.

FIG. 4 is a top view of the hair roller according to this design.

FIG. 5 is a bottom view of the hair roller according to this design.

FIG. 6 is a rear elevation view of the hair roller according to this design; and,

FIG. 7 is a front elevation view of the hair roller according to this design.

A characteristic feature of the design resides in the appearance resemblance to an aerial bombshell.
